UNITED STATES PATENT OFFICE

JOHN H. FOX AND WILLIAM OWEN, OF PITTSBURGH, PENNSYLVANIA, ASSIGNEES TO
PITTSBURGH PLATE GLASS COMPANY, A CORPORATION OF PENNSYLVANIA.

GLASS ROLLING APPARATUS

Application filed May 25, 1932. Serial No. 613,447.

The invention relates to glass rolling apparatus of the general type shown in the Gels-tharp Patent No. 1,615,834, dated February 7, 1927 wherein a sheet of glass is rolled vertically from a molten bath by a pair of sizing rolls which engage the surface of the glass, such glass sheet after formation being directed horizontally through an annealing leer. The invention has for its principal objects 10 the provision of improved means for supporting and driving the sizing rolls in a construction of the character specified. One embodiment of the invention is shown in the accompanying drawings, wherein:

15 Figure 1 is a side elevation of the apparatus. Fig. 2 is a section on the line II—II of Fig. 1. And Fig. 3 is an enlarged section taken at the same point as the section of Fig. 2.

20 Referring to the drawings, 1 is the draw pot or receptacle containing a molten bath of glass 2 which is supplied from a melting tank to the right of the construction shown in Fig. 1. The rolling of the glass is accomplished by means of a pair of sizing rolls 3, 4 positioned with their lower peripheries in a glass bath 2. The glass sheet 5 as it is formed passes up over a series of apron rolls 6, 6, 6, etc. and is then carried downward and 25 through a roller leer of a type well-known in the art. The sizing rolls and the driving mechanism therefor are carried by a fixed framework made up of the vertical posts 7, 7 with suitable cross ties and a movable framework 8 mounted for vertical adjustment with 30 respect to the framework, this being accomplished by means of four screws 9 which are operated by suitable worm gearing in the casings 9*. This also serves to level the apparatus, each set of gearing being operated by 35 means of a hand crank 10. The roll 3 is supported in a pair of rigid arms 11 depending from the framework 8 at the opposite sides thereof, only one of such arms being shown, 40 while the roll 4 is supported for movement toward and from the roll 3 in a pair of arms 12, 12 also mounted at the opposite sides of the frame 8 and pivoted at 13, 13 to the fixed arms 11, 11.

45 The arms 12, 12 are adjusted by means of

screws 14, 14 swivelled in blocks 15, 15 and engaging the springs 16, 16 whose other ends engage the upper ends of the arms 12, 12. Adjustable stop screws 17, 17 serve to fix the 55 relative positions of the rolls 3 and 4.

Each of the rolls comprises a body portion 18 and a pair of end spindles 19. Figs. 2 and 3 illustrate the driven end of the roll 3. The corresponding end of the roll 4 is not driven, the other end of such roll 4 being driven so 60 that there is a drive means for each roll, such drive means being located at opposite sides of the apparatus. The spindle 19 at the driven end of each roll is provided with a pair of water supply swivels 20 having connection with the interior of the spindle and roll. Water is circulated into the pipe 21, passing through the spindle and roll and is discharged through the pipe 22. The specific means for distributing the water through 65 the roll not being illustrated as any suitable means, a number of which are known in the art, may be employed.

70 The fixed arm 11 is provided with a hollow water cooled bearing 23 located closely adjacent the body portion of the roll and supplied with a pair of water circulating pipes 24 and 25. Outward of this bearing is a sprocket 26 for driving the apron rolls 6, 6, 6, etc. This is accomplished by means of a sprocket 75 chain 27 passing over a sprocket 28 on one of the rolls 6. The other apron rolls are driven from this roll by means of sprocket chains 29 and 30. The specific method of 80 drive has nothing to do with the present invention.

85 Intermediate the bearing 23 and the swivels 20 is a worm wheel 31 keyed to the spindle 19 and surrounded by the gear casing 32. This gear casing also acts as a journal for 90 a worm (Fig. 1) lying to one side of the worm wheel and driven from a stub shaft 33. This shaft 33 is connected to another shaft 34 by means of the universal joint 35 and the shaft 34 is driven from the shaft 36 through the 95 universal joint 37. The upper end of the shaft 34 has a splined engagement with the lower member of the universal joint so that the shaft is free to move up and down. The shaft 36 is driven from the shaft 38 (Fig. 1) 100

through the intermediary of the bevel gearing 39, the shaft 40, the bevel gearing 41, the shaft 40a and the bevel gears 41a. The roll 4, whose driven end lies at the opposite 5 side of the machine, is similarly driven by suitable gearing including an extension of the shaft 40 and the bevel gearing 42.

The gear casing 32 is supported by means of a link 43 pivoted at 44 at its upper end 10 to the bearing 45, which carries the shaft 36. The lower end of the link is connected to the gear casing by a ball joint 46.

The ball joint connection 46 permits the casing 32 to adjust itself to the movement of 15 the outer end of the spindle 19. Due to the fact that the rolls 3 and 4 are necessarily of small diameter due to considerations recognized in the art, there is a tendency of these rolls to warp or sag slightly, which results 20 in a wobbling action of the outer ends of the spindles in rotating. Unless provision is made for this wobbling action, binding occurs and undue wear upon the driving mechanism. The mounting of the casing as above 25 described takes care of this condition. This condition is also taken care of in so far as the drive is concerned by the use of the universal joints 35 and 37 and the sliding engagement of the shaft 34 with the lower member 30 of the universal joint 37. The location of the bearings 23 relatively close to the body portions of the rolls is advantageous as it reduces the tendency of the rolls to sag or deflect between the bearings. The deflection is in part due to the weight of the rolls and 35 in part to the pressure exerted by the glass between the rolls which tends to spread them and give a sheet of unequal thickness. The bearings are preferably water cooled in order 40 to protect them from the heat, although this may be dispensed with in some cases. Further protection may also be provided for the bearings in the form of the shields 47 of metal or insulating material. Other advantages incident to the construction will be apparent 45 to those skilled in the art.

What we claim is:

1. In combination in a vertical glass rolling apparatus including a pot or receptacle 50 for carrying a bath of molten glass and a pair of hollow sizing rolls disposed over the bath and each comprising a body portion with a spindle at each end, means for supporting the rolls at the ends comprising arms having 55 bearings engaging the spindles adjacent the body portion of the roll, a driving gear on one of said spindles outward of the bearing on such spindle, a gear casing mounted on the spindle around said gear, a support for the casing permitting universal movement thereof, a second gear journaled in the casing in driving engagement with the 60 first gear, driving means for the second gear including a universal connection, and water supply connections swivelled to the spindle outward of said casing.
2. In combination in a vertical glass roll- 65

ing apparatus including a pot or receptacle for carrying a bath of molten glass and a pair of hollow sizing rolls disposed over the bath and each comprising a body portion with a spindle at each end, means for supporting the 70 rolls at the ends comprising arms having bearings engaging the spindles adjacent the body portion of the roll, a worm wheel on one of said spindles outward of the bearing on said spindle, a gear casing mounted on said spindle around said gear, a worm journaled in the casing in driving engagement with the worm wheel, a support for the casing permitting universal movement thereof, and driving connections for the worm including a 75 universal joint.

3. In combination in a vertical glass rolling apparatus including a pot or receptacle for carrying a bath of molten glass and a pair of hollow sizing rolls disposed over the bath and each comprising a body portion with a spindle at each end, means for supporting the rolls at the ends comprising arms having water cooled bearings engaging the spindles adjacent the body portion of the roll, a worm wheel on one of said spindles outward of the bearing on said spindle, a gear casing mounted on said spindle around said gear, a worm journaled in the casing in driving 85 engagement with the worm wheel, a support for the casing permitting universal movement thereof, and driving means for the worm including a shaft mounted for endwise movement and a universal joint intermediate the worm and the shaft. 90

4. In combination in a vertical glass rolling apparatus including a pot or receptacle for carrying a bath of molten glass and a pair of hollow sizing rolls disposed over the bath and each comprising a body portion with a spindle at each end, means for supporting the rolls at the ends comprising arms having water cooled bearings engaging the spindles adjacent the body portion of the roll, a driving gear on one of said spindles outward of the bearing on such spindle, a gear casing mounted on the spindle around said gear, a support for the casing permitting universal movement thereof, a second gear journaled in the casing in driving engagement with the 100 first gear, driving means for the second gear including a universal connection, and water supply connections swivelled to the spindle outward of said casing. 105

In testimony whereof, we have hereunto 110 subscribed our names.

JOHN H. FOX.
WILLIAM OWEN.
